ANTENNA

Harold A. Wheeler, Great Neck, N. Y., assignor
to Hazeltine Corporation, a corporation of Dela-
ware

Application October 20, 1937, Serial No. 169,922

11 Claims. (Cl. 250—33)

This invention relates generally to an antenna for modulated-carrier signal-translating apparatus and, particularly, to an antenna to be used for very short wave signal-translating apparatus, such as television apparatus.

The reception of television signals is, as a practical matter, restricted to the reception of the ground wave of the transmitter. This is for the reason that a reflected wave of any considerable amplitude will, when added to the ground wave, cause fading which seriously interferes with the receiving system. Therefore, it is desirable that television-transmitting apparatus be designed, in so far as possible, so that the radiated energy will be concentrated in a horizontal plane. However, antennae designed for this purpose generally have undesirable directional characteristics in the horizontal plane, so that their signal field strength varies widely at receiving stations which are equidistant from the transmitter, but in different directions.

It is an object of the invention to provide an antenna for the radiation or reception of horizontally polarized waves which are concentrated in a horizontal plane, but which are nondirectional in that plane.

In accordance with the invention, an antenna comprises a loop in a horizontal plane having, preferably, the approximate configuration of a lemniscate or figure-8. A vertical array of such loops having their longitudinal axes angularly displaced around the vertical is preferable. In a preferred embodiment, the loops are vertically spaced by a distance approximately equal to one-half the wave length of the signal frequency and the cross-over point of each loop in the array is connected to a vertical transmission line so that consecutive loops are at consecutive voltage maxima on the transmission line, that is, points which have maximum voltage of opposite polarity.

For a better understanding of the invention, together with other and further objects thereof, reference is had to the following description taken in connection with the accompanying drawing, and its scope will be pointed out in the appended claims. Fig. 1 of the drawing is a perspective view of a portion of an antenna constructed in accordance with the invention, while Fig. 2 is a perspective view of a further modification of the antenna of the invention.

Fig. 1 of the drawing comprises a four-wire vertical transmission line having two pairs of conductors 10, 11 and 12, 13 disposed at the edges of a square prism. Horizontal loops 14 and

15, each having the approximate configuration of a lemniscate or figure 8, are connected to the transmission line, preferably at points thereon having a vertical displacement equal to one-half the wave length of the signal to be transmitted or received. A signal-translating device 16, forming no part of the present invention, which may comprise a translating circuit of a transmitter or receiver, is shown in dotted lines connected to the transmission line 10, 11 and 12, 13. The length of the wire contained in each half of each loop is also preferably equal to one-half the wave length of the signal. As the capacitive effect of a horizontal loop transmitting antenna alters its directive characteristics, both with regard to the amplitude of a radiated wave and with regard to its plane of polarization, it is desirable that such effect be as small as possible. The capacitance effect in a loop antenna may be minimized by applying to the terminals of the loop a voltage balanced with respect to ground. The center point of the loop is then at ground potential. In the case of a double loop, that is, a loop having the approximate configuration of a lemniscate or figure 8, the two ends operate effectively in parallel in the horizontal plane and have additive magnetic effects, but opposing capacitive effects. If consecutive vertically spaced loops are angularly displaced around the transmission line, further compensating capacitance effects are obtained, thus further tending to produce a substantially nondirectional characteristic in a horizontal plane. It will be seen that the antenna shown in the drawing meets these requirements. Thus, wires 10 and 11, comprising one side of the transmission line, feed one side of each of the loops 14 and 15, while wires 12 and 13, comprising the other side of the transmission line, feed the other side of each of the loops. A voltage balanced with respect to ground is impressed between the conductors 10, 11 and 12, 13 in the case of a transmitter, or is developed therebetween in the case of a receiver. The two pairs of feed wires provide geometrical symmetry and thus further reduce capacitive effects. Loop 14 is angularly displaced 90 degrees about the axis of the system with respect to loop 15 and the wires of the transmission line 10, 11 and 12, 13 are connected to loops 14 and 15 adjacent the cross-over point of each loop. Instantaneous polarities are indicated by the plus and minus signs in the drawing and the direction of current flow around the loops at this instant is shown by the arrows.

While there has been shown an array of two double loops, it will be understood that any num-

ber of loops can be used to effect the desired concentration of radiation in the horizontal plane and an antenna having four or eight double loops is suggested, an even number being preferred.

5 In considering the operation of the antenna described above, it will be noted that opposite halves of each of the double loops carry currents which are in the same direction around the loops, for example, counterclockwise, and thus 10 have additive electromagnetic and electrostatic radiation effects in the horizontal plane. Adjacent vertically spaced loops have terminals oppositely connected to the wires of the transmission line, but as the loops are spaced a half-wave 15 length, the voltage applied to the loops is also reversed so that the magnetic effect of the loops add in a horizontal plane.

While the invention has been described with 20 respect to an array of horizontal loops having the approximate configuration of a lemniscate or figure 8, it will be understood that applicant does not wish to limit his invention to an array of loops having this particular shape, but that the invention is equally applicable to any array of 25 horizontally disposed loops.

Furthermore, while a four-wire vertical feed line has been shown as preferable, some of the 30 advantages of the invention may be obtained by using a two-wire line or a single vertical wire with the vertically consecutive loops disposed at voltage maxima of opposite polarity, so that the required direction of current flow in each half of the loops is obtained. An antenna structure comprising a single vertical feed wire is shown in 35 Fig. 2 of the drawing. The antenna of Fig. 2 is generally similar to that of Fig. 1 and similar elements have been given identical reference numerals. The antenna of Fig. 2 comprises horizontal loops 14 and 15 disposed at voltage maxima 40 of opposite polarity along the vertical feed wire 18. In considering the operation of the antenna of Fig. 2, it will be seen that the principle involved is the so-called "voltage feed" principle, which is commonly employed in feeding simple 45 aerials, such as doublets, either singly or in complicated arrays. This principle is applicable to the antenna of Fig. 2 because each loop is merely two half doublets or one whole-wave doublet bent around to form a figure 8. The voltage feed 50 principle is based on feeding the antenna at a point of maximum impedance. The impedance is so high that the current flowing into the antenna is very small. The current is so small that it returns to ground through the capacitance in open 55 space. Each loop has maximum impedance between its terminals which may be considered as the adjacent cross-over points, at the operating frequency. Each loop is connected at a voltage maximum point along the transmission line. At 60 such maximum voltages, very little current flows in each loop in order to supply its power.

While there has been described what is at present considered to be the preferred embodiment of the invention, it will be apparent to those 65 skilled in the art that various changes and modifications may be made therein without departing from the invention, and it is, therefore, aimed in the appended claims to cover all such changes and modifications as fall within the true spirit and scope of the invention.

70 What is claimed is:

1. A high-frequency signal-radiating antenna comprising conductors having the approximate configuration of a figure 8 and having terminals 75 on said conductors adjacent their cross-over

point, the loops of said figure 8 being effectively connected in parallel with respect to said terminals.

2. A signal-translating antenna comprising 5 conductors having the approximate configuration of a figure 8 disposed in a horizontal plane, whereby said conductors are symmetrically disposed with respect to ground, said antenna having terminals on said conductors adjacent their cross-over point.

3. In combination, a signal-translating antenna comprising conductors having the approximate shape of a figure 8 and a single-wire transmission line, said antenna having one of the conductors thereof connected at the cross-over point 15 to said transmission line at one of the voltage maxima of said line.

4. In combination, a high-frequency signal-radiating antenna comprising conductors having the approximate configuration of a figure 8, and a balanced transmission line having conductors connected, respectively, to the conductors of said antenna adjacent their cross-over point, the loops of said figure 8 being effectively connected in 20 parallel with respect to said terminals.

5. In combination, an array of vertically spaced antennae each comprising conductors having the approximate shape of a figure 8, and a single-wire transmission line, each of said antennae having one conductor thereof connected 30 at the cross-over point to said transmission line at one of the voltage maxima of said line.

6. In combination, an array of vertically-spaced antennae each comprising conductors having the approximate shape of a figure 8, and a single-wire transmission line, each of said antennae having one conductor thereof connected 35 at the cross-over point to said transmission line at one of the voltage maxima, the individual loops of each of said antennae having a length approximately equal to one-half wave length of the operating signal.

7. In combination, an array of vertically-spaced loop antennae, and a balanced transmission line having conductors individually connected to the terminals of said antennae, said antennae being spaced along said transmission line a distance approximately equal to one-half wave length of the operating signal and having axes of symmetry through said transmission line 50 and angularly displaced about said line.

8. In combination, an array of vertically-spaced antennae each comprising conductors having the approximate shape of a figure 8, and a balanced transmission line having conductors connected respectively to the conductors of each of said antennae adjacent the cross-over point, said antennae being spaced along said transmission line a distance approximately equal to one-half wave length of the operating signal and 55 having axes of symmetry angularly displaced about said line.

9. In combination, an array of antennae each comprising conductors having the approximate shape of a figure 8, and a balanced transmission 60 line having conductors connected respectively to the conductors of each of said antennae adjacent the cross-over point, said individual antennae being spaced along said transmission line a distance approximately equal to one-half wave 65 length of the operating signal, and the individual loops of each of said antennae having a length of conductor approximately equal to one-half of said wave length.

10. In combination, an array of vertically- 75

5 spaced antennae each comprising conductors having the approximate shape of a figure 8, and a balanced transmission line having conductors symmetrically connected respectively to the conductors of each of said antennae adjacent their cross-over point, said individual antennae being spaced along said transmission line a distance approximately equal to one-half wave length of the operating signal.

11. In combination, an array of antennae each comprising conductors having the approximate shape of a figure 8, and a balanced four-wire transmission line having conductors symmetrically connected respectively to the conductors of each of said antennae adjacent the cross-over point, said individual antennae being spaced along said transmission line. 5

HAROLD A. WHEELER.
